UNITED STATES PATENT OFFICE.

JOHN A. HEALY, OF LANGDON, AND JAMES H. HEALY, OF ST. PAUL, MINNESOTA.

RADIATOR HANGER.

Application filed April 5, 1920. Serial No. 371,292.

To all whom it may concern:

Be it known that we, JOHN A. HEALY and JAMES H. HEALY, citizens of the United States, residing, respectively, at Langdon, 5 county of Washington, and at St. Paul, in the county of Ramsey, and State of Minnesota, have invented new and useful Improvements in Radiator Hangers, of which the following is a specification.

10 Our invention relates to improvements in radiator hangers.

In hanging radiators from a wall it is preferable from the standpoint of security and economy to embed suspension bolts in 15 the brick or concrete as the wall is erected. The proper locating of such bolts is difficult, however, until the interior finishing has been completed. If such time be chosen for the installation of suspension means, holes must 20 be carefully drilled and expansion shields or similar bolts employed. Such method is slow, expensive, and inefficient, and if the bolts be placed during the erection of the wall difficulty in alining the hangers from 25 the frequently misplaced bolts is experienced.

Our object is to provide a strong and economical hanger possessing novel means for securing a radiator in proper alinement with the wall.

30 A further object is to provide adjustable means for off-setting a radiator from the wall to clear an obstruction such as a baseboard or moulding.

Another object is to supply means for adjusting radiators vertically and longitudinally from a previously positioned bolt or socket embedded in a brick or concrete wall.

These and other objects will more fully hereinafter appear in the following specification.

40 In the accompanying drawings Figure 1 is an end view of our hanger showing it attached to a wall, supporting a radiator indicated in dotted lines; Fig. 2 is a front view 45 of the hanger with the retaining bolt and disc removed; Fig. 3 is a vertical section through the box frame and a portion of the cement wall to which it is attached, with a portion of one of the tubes of a radiator shown in dotted lines; Fig. 4 is a front view 50 of the retaining disc and bolt together with portions of the adjoining tubes of a radiator; Fig. 5 is a view of the retaining bolt and disc showing the disc in the position for inserting it between the tubes of a radiator; 55 Fig. 6 is a view of the same in the position

for engaging the tubes of a radiator; Fig. 7 is a horizontal section through the offset sleeve and vertical pipe; and Fig. 8 is a horizontal section of the box frame taken on 60 the line 8-8 of Fig. 2.

Referring to the drawings, we have used the numeral 1 to indicate a box frame, 2 vertical suspension pipe or rod, 3 an offset sleeve, 4 a lower supporting bracket, 5 a retaining bolt and 6 a retaining disc. The letter R represents a radiator of ordinary type.

The box frame 1 is suspended from an anchor bolt 8 (Figs. 1 and 3) which passes through a slot 7 (Fig. 2) in said frame, and has a nut 9 which holds the frame 1 against the wall. The anchor bolt 8 is secured in suitable manner in the wall. Studs 12 (Figs. 1 and 8) are cast integral with the frame 1 and project into recesses in the wall to 75 secure said frame against tilting motion on the wall. The body of the frame 1 is in the shape of an open box having a slot 10 (Fig. 2) to receive the inner end of the retaining bolt 5, as shown in Fig. 3, and a slot 11 (Figs. 8 and 3) to receive the upper end of the vertical pipe 2. The vertical pipe 2 is threaded at its upper end to receive a hexagonal nut 13, passes through the offset sleeve 3 and sleeve 14 of the bracket 4, and is 80 threaded to receive a cap 15 at its lower end. The hexagonal nut 13 is supported in a channel formed by two grooves 16, one on either side of the slot 11 in the frame 1 so as to prevent said nut from turning but 85 allowing longitudinal adjustment in the frame.

The offset sleeve 3 is provided to hold the lower end of the vertical pipe 2 away from the wall and the sleeve 14 of the lower 95 bracket 4 away from the moulding 17. The sleeve 3, as shown in Fig. 7, has flanges 18 and 19 formed integral therewith, and is adjustable vertically by sliding on the rod 2.

The flanges 18 abut against the wall and 100 the flanges 19 abut against adjacent radiator tubes, as shown in Fig. 1.

The lower bracket 4 extends under the lower horizontal pipe of the radiator R to carry the weight of said radiator and is 105 formed with the sleeve 14 through which the vertical pipe 2 passes. The sleeve 14 of the lower bracket 4 is slidable on the pipe 2 and supported by the cap 15 which is screwed over the lower end of said pipe.

The retaining bolt 5, together with the disc 6, (Figs. 3, 4, 5 and 6) is provided to

hold the upper portion of the radiator R from tilting away from the wall.

The bolt 5 passes through a hole in the center of the disc 6, between two radiator tubes, extends through the notch 10 in the box frame 1, and is secured by a nut 20 within said frame 1. The head 5^a of said bolt 5 engages the disc 6 to hold said disc in contact with adjacent tubes of the radiator R.

The disc 6 is designed to be turned, as shown in Fig. 5, to lie substantially in the same plane with the axis of the bolt 5 so that it may be easily inserted between the tubes 15 of a radiator and then turned to the position shown in Figs. 4 and 6 to engage the radiator tubes. After the disc 6 has been placed in this position the nut 20 is screwed on the inner end of the bolt 5, as shown in Fig. 3, thus securing the radiator R from tilting away from the wall. Two or more of my hangers are placed at intervals to support radiators of various lengths. The slot 7 permits a certain amount of vertical 20 adjustment, and further adjustment in this direction is secured by making it possible to turn the nut 13 a greater or less distance on the threaded upper end of the pipe 2. Lateral adjustment is permitted by the slots 25

10 and 11 in the box frame 1 which allow 30 the retaining bolt 5 and vertical pipe 2, together with the offset sleeve 3 and lower bracket 4, to be placed at any desired point. Thus, any misplacing of the anchor bolt 8 may be counteracted by proper adjustment 35 of our hanger.

Having described our invention what we claim as new and desire to protect by Letters Patent is:

In a hanger, the combination of a frame 40 arranged to be secured to a wall, a substantially vertical and transversely adjustable rod suspended from said frame, a bracket for supporting a radiator on the lower end of said rod, an off-set/separate from said 45 bracket and slidably mounted on said rod above said bracket adapted to engage said rod above a base board to maintain its vertical position and a transversely adjustable bolt secured in said frame and arranged to hold a radiator toward the wall, the adjustment of said bolt being independent of the adjustment of said vertical rod.

In testimony whereof, we have hereunto subscribed our names to this specification.

JOHN A. HEALY.
JAMES H. HEALY.
